SHEET-METAL BUTTON AND THE METHOD OF MAKING THE SAME

Application filed August 6, 1928. Serial No. 297,807.

My invention aims to provide improvements in buttons and particularly sheet metal buttons and the method of making the same.

5 In the drawings illustrating my invention:—

Figure 1 is an elevation view of a button secured to a button-carrying medium;

Fig. 2 is a section taken on the line 2—2 10 of Fig. 1, the tack being shown in elevation;

Fig. 3 is a section of a slightly modified form of button;

Fig. 4 is a part section and part elevation showing the manner of attachment of the button to a carrying medium, portions of the assembling dies being shown in section;

Fig. 5 shows a sheet metal disc from 20 which a button is formed;

Figs. 6 through 13 show various dies between which the blank is passed step by step to form a complete one-piece button, the plan views showing the shape which a 25 blank takes after being pressed between the dies shown below.

Fig. 14 shows a button body with an apertured cap attached; and

Fig. 15 shows a button body with an im- 30 perforate cap attached and a plate inside the head of the button back-supporting the tack turning and clenching means.

Referring to the embodiment of my invention illustrated by the drawings, I have 35 shown a button which is particularly adapted to be secured to garments or other material by means of a metallic fastening device turned and concealed by an anvil portion in the button.

40 Heretofore buttons of this class have been formed from sheet metal and also from solid bar stock. The sheet metal buttons have been formed with a body part and a separate anvil part secured in various ways 45 to the body part. Therefore, at least two separate pieces were required to provide the body and anvil portion. Buttons presenting one-piece body and anvil portions have been made from bar stock, but they are somewhat difficult to manufacture and are rather

heavy as compared with a sheet metal button.

My invention, as illustrated by the drawings, is directed to a sheet metal button which has the anvil or turning and clenching means formed integral with the body part of the button and also relates to the method of making such a button.

The body part may constitute the entire button or may be the body or back portion 55 of a plural-part button when combined with a whole or partial cover part, as shown in Figs. 14 and 15 which are described more in detail in my co-pending applications Serial No. 297,808 and Serial No. 297,809 60 filed herewith.

The button illustrated by Figs. 1 and 2 has a body portion which includes the head 1 (being the part which passes through a buttonhole), a cup-shaped shank 2 formed integral with the head, and an anvil portion 3 formed integral with the shank 2. The double wall portion 4 at the bottom of the shank is turned inwardly to provide a 65 restricted opening 4^a into the chamber 5 which receives the metallic fastening element.

In this instance I have shown (Figs. 2 and 4) a tack 6, which may be of any suitable structure, piercing a suitable carrying medium 7 and having its pointed end portion upset by the anvil portion to form a curled portion 8. This curled portion 8 cooperates with the inturned double wall portion 4 to hold the button in place upon the carrying medium 7.

In attaching the button to the carrying medium 7, I may use a hand tool or automatic machine (not shown) having a tack holding die 9 (Fig. 4) and a die 10, which fits into the mouth of the shank 2. Therefore, when the dies are forced toward each other the tack 6 will be forced through the carrying medium 7 into the chamber 5 where the pointed portion will be upset, as shown in Fig. 2. During the preferred attaching operation illustrated the die 10 back-supports the anvil portion 3 and where the body is formed of brass or other 95 relatively soft metal serves to prevent the 100

tack from piercing the anvil portion. When the attachment is complete the shank of the tack is concealed and the button presents a neat and finished appearance and there is no portion of the tack exposed which may rust and become unsightly.

Referring now to the method of making the body portion with the integral anvil, as shown in step-by-step form in Figs. 5 through 13, I have illustrated various dies which perform the various operations. The flat blank shown in Fig. 5 is first passed between the dies 11 and 12 (Fig. 6) which cup the blank, as shown in cross-section. The cup-shaped part then passes between dies 13 and 14, shown in Fig. 7, where the head and cup-shaped shank 2 are formed. In this form it is passed between the dies 15 and 16 (Fig. 8) and the bottom of the cup-shaped shank 2 is pressed toward the open end of the cup to begin the formation of the anvil or clenching and turning means. The blank next passes between the dies 17 and 18 (Fig. 9) and the dies 19 and 20 (Fig. 10) to complete the process of pressing the bottom of the cup-shaped portion toward the mouth of the shank and form the double thickness wall portion 4. In Fig. 11, the dies 21 and 22 turn the wall portion 4 inwardly toward the center of the shank and against the projection 23 on the die 22 to form the restricted opening 4^a surrounded by a substantially perpendicular wall. The button is complete at this stage, but I prefer to provide the head 1 with a rounded flange 24, so I pass it from between the dies 21 and 22 through the dies 25 and 26 (Fig. 12) and between the dies 27 and 28 (Fig. 13) where the flange is completed and the button is then turned out complete from a single piece of sheet metal.

My improved button and the method of forming the same are simple and, while I have shown a complete one-piece sheet metal button, my invention is more particularly directed to the formation of the anvil means as an integral part of the body of a button which is pressed from sheet metal. The shape of the head 1 of the body may be varied, preferred forms being shown in Figs. 2 and 3. The head of the body may be covered by another piece of metal or fabric or the like if desired, preferred forms being shown by Figs. 14 and 15 and in my applications hereinbefore referred to as filed herewith.

While I have illustrated and described my invention somewhat in detail, I do not wish to be limited thereby as the scope of my invention is best defined in the following claims.

Claims:

1. A metal button having a body formed of sheet metal, said body having as integral parts thereof, a head, a shank having a re-

stricted opening at the bottom end thereof, and a generally arch-shaped anvil portion housed within and integral with said shank, said anvil portion providing a fastener-receiving recess in which a fastening element 70 may be upset.

2. A button having a body pressed from a single piece of sheet metal, said body having a head, a shank formed integral therewith, an anvil portion housed within and integral with the shank and inwardly turned means joining the shank and anvil portion and forming a restricted opening. 75

3. A button having a body pressed from a single piece of sheet metal, said body having a head, a shank formed integral therewith, an anvil portion housed within and integral with the shank and inwardly turned means joining the shank and anvil portion and forming a restricted opening, and means 80 providing an opening in the head of said body to expose the anvil portion so that it may be back-supported during attachment of the button to a support. 85

4. A button having a body of substantially uniform thickness throughout its entire formation, said body having a head, a cup-shaped shank integral with said head, a hump formed in and integral with the bottom portion of said cup-shaped shank to provide a chamber in which the upset portion of an attaching element is housed when the button is attached to a support and a ledge providing a restricted opening at the bottom of said chamber. 90

5. A button having a body of substantially uniform thickness throughout its entire formation, said body having a head, a cup-shaped shank integral with said head, a hump formed in and integral with the bottom portion of said cup-shaped shank to provide a chamber in which the upset portion of an attaching element is housed when the button is attached to a support and a double wall turned inwardly at the bottom 105 end of said cup-shaped shank to provide a restricted opening into said chamber, said hump also providing means for upsetting an attaching element. 110

6. A one-piece button formed entirely from a single piece of sheet metal and having a head, a cup-shaped shank integral with said head, an anvil portion pressed from and formed integral with the bottom of said cup-shaped shank, and inwardly turned means at the bottom end of said shank providing a restricted opening to guide the shank of an attaching element into engagement with said anvil portion to be upset by the anvil portion and said inwardly turned means preventing withdrawal of the upset portion of the shank. 115

7. The method of forming a sheet metal button having a head, a cup-shaped shank and anvil means, which comprises pressing 120

the bottom of the cup-shaped shank toward the mouth of the cup-shaped shank and then turning the lower edge of the shank inwardly to form a restricted opening.

5 8. The method of forming a sheet metal button having a head, a cup-shaped shank and anvil means, which comprises pressing the bottom of the cup-shaped shank toward the mouth of the cup-shaped shank 70
10 to form a pocket surrounded by a wall of double thickness and then turning the free edge of the double thickness wall inwardly to provide a restricted opening in the bottom end of the shank.

15 9. The method of forming fastener receiving and clinching means in a button having a cup-shaped shank which comprises pressing the bottom of the cup-shaped shank toward the open end thereof and then turning 75
20 in the edge of the wall to provide a chamber having a restricted opening.

10. The method of forming fastener receiving and clinching means in a button pressed from a single piece of sheet metal 80
25 which comprises pressing the metal to provide a cup-shaped shank, pressing the bottom of the cup-shaped shank toward the open end of the shank to provide a wall of double thickness and then turning inwardly 85
30 said double thickness wall to provide a chamber having a restricted opening.

11. The method of forming a pressed sheet metal button having a one-piece body provided with a head, a cup-shaped shank 90
35 and anvil means, which comprises pressing the bottom of said cup-shaped shank toward said head and turning inwardly the bottom peripheral edge of said cup-shaped shank to provide a restricted opening in the 95
40 bottom end of said button.

12. The method of forming a pressed sheet metal button having a one-piece body provided with a head, a shank and anvil means within the shank, which comprises 100
45 passing a flat blank of sheet metal through a series of dies to form the head and shank, pressing the anvil means from a portion of the blank so that it is located within the shank and forming a restricted opening in 105
50 the bottom of the shank by turning the lower edge of the shank inwardly.

13. A button having a body pressed from a single piece of metal and having a top flange, a cup-shaped shank extending downwardly from said flange, a double wall portion extending inwardly at the bottom of said shank and surrounding an aperture, a fastener element-turning portion curved upwardly from said bottom and housed within 110
55 said shank to enclose an enlarged space above said aperture in which a fastener element may be upset.

14. A button having a body pressed from a single piece of sheet metal, said body having 115
60 a head, a shank formed integral there-

with, an anvil portion housed within and integral with the shank and inwardly turned means providing a double thickness of metal and joining the shank and anvil portion, said inwardly turned means forming a restricted opening. 70

15. A button having a body pressed from a single piece of sheet metal, said body having a head having a rolled edge, a shank formed integral therewith, an anvil portion housed within and integral with the shank and inwardly turned means at a substantially right angle to the axis of the button and joining the shank and anvil portion and forming a restricted tack-receiving opening. 75

In testimony whereof, I have signed my name to this specification. 80
